MAP TRANSPARENCY CURVATURE DEVICE
Louis D. Tangorra, Bronx, N.Y., assignor, by mesne assignments, to the United States of America as represented by the Secretary of the Navy

Filed Oct. 23, 1961, Ser. No. 147,108

9 Claims. (Cl. 18—19)

The present invention relates to curvature devices and more particularly to devices for curving flexible members to prescribed arcs.

In map making it sometimes becomes desirable to take flat maps made by taking conic projections of a spherical globe and produce curved models therefrom. The usual procedure is to draw the map on a piece of flat clear plastic to conform to its drafted conic section, and by means of a projection system, on the sensitized surface of a curved model, use the curved map to produce a photographic image. Curving of the transparency is done by stretching the plastic over a support conforming to the curve of the particular conic projection. Obviously, it can be seen that if a number of models using maps of different projections are to be made, the step of producing the conic support becomes expensive and time consuming. Thus, it becomes desirable to develop a support which can shape the plastic transparency to suit any number of different conic sections. In addition, these supports must have certain features necessitated by the nature of their function. For instance, the supports must not interfere with the projection of the transparency onto the sphere and since the transparency must conform to a conic section the device must be able to curve it to more than one radius of curvature.

Therefore, it is an object of the present invention to produce a support which conforms objects to a number of curvatures.

Another object of the instant invention is to produce a support whose radius of curvature may be quickly and accurately changed.

Still another object of the instant invention is to produce a curvature device whose radius of curvature may be easily determined.

Other objects and many of the attendant advantages of this invention will be readily appreciated as the same becomes better understood by reference to the following detailed description when considered in connection with the accompanying drawings wherein:

FIG. 1 is a side elevation of the present invention; FIG. 2 is a section taken along 2—2 in FIG. 1; and FIG. 3 is a section taken along 3—3 in FIG. 1.

Referring to the figures, a spring steel bar 10, which serves as the curve support of the transparency, is attached at its center 12 by means of a pin dowel 14 and clamp 16 to an arcuate pivot 18 which conforms to the minimum desired radius of curvature. The arcuate pivot 18 is preferable to a knife edge support located at the center of 16 of the bar since the bending of the bar around such a support tends to form the bar to a hyperbolic function. The curved pivot decreases the tendency of the bar to take such hyperbolic form. Likewise, the bar is tapered towards its ends 20 and 22 to similarly minimize the tendency of the bar to take hyperbolic form.

The bending force to produce curvature is brought at each end 20 and 22 of the bar 10 by means of pivoted rods 24 and 26 which are notched 28 at the ends to accept circular cams 30 and 32 attached to plates 34 and 36 depending from the ends of the bar 10. The unnotched ends of the bars 24 and 26 are formed into sector gears 38 and 40 that mesh with the output gears 42 and 44 of a gear system driven by a shaft 46 attached to a knob

2

48 that may be turned by an operator. Thus, rotation of the knob 48 will move the sector gears 38 and 40 pivoting the rods 24 and 26 around their pivots so that the notched ends of the rods 24 and 26 bring pressure to bear on the circular cams 30 and 32 to bend the bar 10. A counter 50 attached to the knob 48 by a beveled gear set 52 will measure the position of the knob for a given curvature so that the knob may be calibrated in terms of the arc described by the bar 10.

10 In operation, the arcs prescribed by the two curved extremities of a conical section are determined. The bars 10 in two devices similar to the one described are bent to conform to these arcs by rotation of the knobs 48 in each of the devices. One bar conforms to one extremity and the other bar to the other extremity. These supports are then attached to the edges of the transparency which is to be curved. The transparencies are then ready for projection.

20 Obviously many modifications and variations of the present invention are possible in the light of the above teachings. It is therefore to be understood that within the scope of the appended claims the invention may be practiced otherwise than as specifically described.

What is claimed is:

25 1. A device to be used in pairs to bend transparent maps to curve them to their drafted scale curvature preparatory to their projection on sensitized models comprising,

30 a flexible bar to which the edges of a transparent map may be attached, means having a curved surface attached to the center of the flexible bar providing a pivot point on which said flexible bar is bendable, and force means coupled to said bar for bending the bar to conform to a desired curve by setting up a bending moment around the pivot point.

35 2. The structure of claim 1, wherein the bar is tapered toward its extremities.

40 3. A device to be used in pairs to bend transparent maps to curve them to their drafted scale curvature preparatory to their projection on a sensitized model comprising,

45 a flexible bar tapering from its center to which the edges of a transparent map may be attached, arcuate curve means conforming to the map section having the smallest radius of curvature coupled to the bar at its center providing a pivot point on which the bar is bendable, and force means coupled to the ends of the flexible bar for bending the bar to the desired curve by setting up a bending moment around the pivot point.

50 4. A device to be used in pairs to bend transparent maps to curve them to their drafted curvature preparatory to their projection on sensitized models comprising, a tapered flexible bar to which the edges of a transparent map may be attached, means having an arcuate curved surface to which the flexible bar is bendably attached at approximately its center thereby providing a pivot point, force means coupled to the ends of the flexible bar for bending the bar to the desired curve by setting up bending moments around the pivot point,

55 and adjusting means coupled to the force means to vary the bending moments to obtain various radii of curvatures.

60 5. The structure of claim 4, including meter means coupled to said adjusting means to determine the radius of curvature of the flexible bar.

65 6. A device to be used in pairs to bend transparent maps to curve them to their drafted scale curvature

preparatory to their projection on sensitized models comprising,

a tapered flexible bar to which the edges of a transparent map may be attached, means having an arcuate curved surface to which the flexible bar is bendably attached at approximately its center thereby providing a pivot point, lever means slidably coupled to the ends of the flexible bar and pivotally secured to said arcuate surface means to bend the flexible bar around the curved surface, 10 and drive means coupled to said lever means to pivot said lever means around said pivot.

7. The structure of claim 6, and including meter means coupled to said drive means to determine the radius of curvature of the flexible bar.

8. An adjustable device to be used to bend map transparencies to various desired radii of curvature preparatory to their projection on sensitized models comprising, a flexible bar to which the edges of a transparent map may be attached, means having a curved surface attached to the center of the flexible bar providing a pivot point on which said flexible bar is bendable,

and means coupled to said bar for bending the bar to substantially conform in shape to the arc of a true circle.

9. The structure of claim 8, wherein the last named 5 comprise; a pair of cam means, each of said cam means being coupled to an end of the flexible bar, a pair of lever means, each of the lever means being coupled at one end to the cam means, pivot means coupled to the curved surface means and the ends of said lever means, and drive means coupled to said pivot means for pivoting said lever means around said pivot point thereby bending the flexible bar to any desired radii of curvature.
